E. W. CHRISTY

DRAWING INSTRUMENT

Filed August 17, 1925

Patented Aug. 3, 1926.

1,594,604

UNITED STATES PATENT OFFICE.

ELMER W. CHRISTY, OF CINCINNATI, OHIO.

DRAWING INSTRUMENT.

Application filed August 17, 1925. Serial No. 50,589.

An object of my invention is to provide a drawing instrument which is particularly adapted to use in laying out drawings upon a vertical blackboard, drawing board or the like.

Another object is to provide a device for the purpose stated, by means of which may be drawn lines in perpendicular and horizontal planes and at various angles thereto.

Another object is to provide a device of this kind, which, though not primarily intended as a precision drawing instrument, is nevertheless very accurate in that all lines drawn thereby are taken from an absolute perpendicular and to this end, errors made by the operator are not multiplied.

Another object is to provide a device of this kind which is simple of construction and inexpensive of manufacture.

Another object is to provide a device of this kind which may be manipulated with greater facility, and is therefore adapted to work of greater accuracy than is ordinarily possible with devices of this kind.

These and other objects are attained by the means described herein and in the accompanying drawings, in which:

Fig. 1 is a plan view of the device of my invention in position for drawing a horizontal line.

Fig. 2 is a similar view showing the device in position for drawing a line at an angle to a horizontal.

Fig. 3 is a similar view showing the device in position for drawing a vertical line.

Fig. 4 is a fragmental cross-sectional view taken on line 4—4 of Fig. 1.

Fig. 5 is an end elevation of the device as shown in Fig. 1.

Fig. 6 is a cross-sectional view taken on line 6—6 of Fig. 4.

The device of my invention comprises an integral scale, straight edge and protractor, which are provided with a rigid handle member mounted midway of the ends of the straight edge. A slotted indicator arm is freely pivoted beneath the handle member and is provided with an indicating point so that the pivotal mounting of the indicator and the indicator point thereof will always lie in a true vertical plane when the device is held against a perpendicular surface, such as a blackboard or the like. The straight edge 10 is provided with suitable graduations 11, which are numbered from zero at

the longitudinal center 12 thereof and extend to the ends 13 and 14. An integral protractor body 15 has its radial center in alignment with the zero point of the straight edge and the 90-degree line 16 of the protractor lies parallel with the working edge of the straight edge 10. The protractor portion 15 is provided with suitable graduations which may be numbered from zero at the central portion thereof up to 90 degrees at the line 16. At the intersection of line 16 and a line extending through the zero markings on the protractor and straight edge is provided a bore 18 and an enlarged concentric counter-bore 19 extending from the rear face 20 of the protractor.

A shouldered threaded nut 21 is adapted to seat in the bore 18 and counter-bore 19 and to lie flush with the rear face 20 of the device. A stud 22 is provided with threads 23 at its opposite ends. Threads 23 are received by a threaded nut 21 thereby serving to secure the stud 22 perpendicularly to the face of the protractor.

A washer 241 spaces the shoulder 30 of stud 22 from the protractor. An arm 25 is provided with an elongated slot 26, into one end of which extends a sharp projection which serves as an indicator point 27. The end 28 of the arm 25 is provided with a bore 29 adapted to receive an enlarged shoulder portion 30 on the stud 22. The shoulder portion 30 of the stud is of a slightly greater dimension than the thickness of the arm 25 so that an end-bearing washer 31 of handle 32 will not bind on the arm 25. The handle 32 may be counter-bored as at 33 for receiving a suitable fastening nut 34, which engages the screw threads 24 and the stud 22.

By reference to Fig. 4 it will be apparent that the stud 22 serves both as a securing means for the handle and as a bearing means for the arm 25. The lower end 35 is relatively heavier than the end 28 thereof and is so weighted that the arm will serve as a plumb with the point 27 always indicating an absolute perpendicular. The elongated opening 26 enables the operator of the device to read the graduations on the protractor and enables him to bring the indicating point 27 and graduations 17 into registry.

The operation of the device is obvious. One using the combined protractor and straight edge would grasp the instrument by

handle 32 and place it against a blackboard or vertical drawing board; should he desire to draw a horizontal line he would turn the device until the indicating point 27 registered with zero on the protractor, whereupon the straight edge 10 would lie in a plane 90 degrees to actual perpendicular. He would then draw a line of a desired length, using the graduations 11 for this purpose. Should he then desire to erect a perpendicular to the horizontal line the device would then be turned by the handle 32 until the indicator point 27 registered with the line 16, whereupon he would be able to draw the line in a true perpendicular plane which would incidentally be at 90 degrees to the horizontal line previously drawn. In the same manner all lines drawn at intermediate angles would have their measurements taken with a true perpendicular as a starting point, so that in the construction of various geometrical figures there would be eliminated the usual multiplication of errors and inaccuracies, which follows the drawing of a line at an angle to a given drawn line and then using the second line as a base for constructing a third line at an angle thereto.

What I claim is:

1. A drawing instrument for use upon vertical blackboards and the like and comprising a semi-circular protractor body, an elongated straight edge member having graduations along its edge at the flat side of the semi-circular body and extending beyond the opposite ends of said side thereof, a stud extending perpendicularly from the radial center of the protractor body and having one end secured thereto, a weighted arm rotatably mounted at one end on the stud and having indicating means at its other end for registry with the graduations on the protractor body, a handle on the free end of the stud and arranged to preclude separation of

the arm from the stud and to preclude binding of the arm between the handle and body. 45

2. In a device of the class described the combination with a body member comprising an elongated graduated straight edge and an integral graduated protractor having a bore and a counter-bore disposed concentrically 50 with the radial center of the protractor of a shouldered nut adapted to seat in the bore and counter-bore in the body member, a stud having threaded end portions, one of which is adapted to screw into the shouldered nut, 55 a shoulder portion on the stud, a spacing washer between the shoulder and the protractor, a handle member carried by the stud and adapted to abut the shoulder portion thereof, means for rigidly securing the handle member to the stud in abutment with the shoulder portion thereof and an arm having a bearing bore at its one end for mounting the arm upon the shoulder portion of the stud, said arm having an elongated aperture 60 at its opposite end and an indicating point disposed at one end of the elongated aperture for registering with the graduations on the protractor as the arm is moved on its pivotal mounting. 65

3. In an instrument of the class described the combination of a body comprising a straight edge and a protractor, a stud extending from the body perpendicular thereto at the radial center of the protractor, an 70 arm provided with indicating means adapted to register with the graduations on the protractor and at one end loosely receiving the stud whereby to permit free movement of the weighted arm about the stud, and handle 75 means carried by the stud for manipulating the body relative to the weighted arm.

In testimony whereof, I have hereunto subscribed my name this 8th day of August, 1925.

ELMER W. CHRISTY.
